DESIGN FOR A WHEELED RACK FOR MAGAZINES, BOOKS, OR THE LIKE

Wilbur Henry Adams, Erie, Pa., assignor to The Colson Corporation, Elyria, Ohio, a corporation of Ohio

Application November 9, 1943, Serial No. 111,636

Term of patent 7 years

To all whom it may concern:

Be it known that I, Wilbur Henry Adams, a citizen of the United States, residing at Erie, in the county of Erie and State of Pennsylvania, have invented a new, original, and ornamental Design for a Wheeled Rack for Magazines, Books, or the like, of which the following is a specification, reference being had to the accompanying drawing, forming a part thereof.

Fig. 1 is a front perspective view of a wheeled

rack for magazines, books or the like, showing my new design; and

Fig. 2 is a side elevational view thereof.

The essential and characterizing features of my design are shown in full lines in the drawing.

I claim:

The ornamental design for a wheeled rack for magazines, books, or the like, substantially as shown and described.

WILBUR HENRY ADAMS.
